PROCESS FOR REFINING SULPHUR-
CONTAINING HYDROCARBON OILS

Henry C. Paulsen, Elizabeth, N. J., assignor to
Standard Oil Development Company, a cor-
poration of Delaware

Application January 24, 1942, Serial No. 428,048

4 Claims. (Cl. 196—30)

This invention relates to a method for sweetening sour hydrocarbon oils, such as gasoline, kerosene, and heating oils, more particularly, for removing objectionable odoriferous and corrosive sulphur components from such oils by treatment with an alkaline aqueous solution containing cupric hydroxide.

The most common sweetening method is the doctor treatment, which consists in treating a sour oil with added sulphur and a caustic solution of sodium plumbite to convert mercaptans, which render the oil sour, into alkyl sulphides. Although the doctor treatment is an effective sweetening process, it has several serious disadvantages. In actual practice, it generally involves the use of added free sulphur to accelerate and complete the reaction (disulphide and lead sulphide formation). This practice leads to an increase rather than a reduction in the total sulphur content of the oil, thus causing sweetened products to be corrosive, and tending to make gasoline fuels have a lower anti-knock value, particularly less response to lead alkyl anti-knock agents.

A general object of this invention is to provide a sweetening treatment which is satisfactory for various types of petroleum oil distillates and which does not require an addition of sulphur. Another object is to provide a refining process capable of effectively reducing the total sulphur content of an oil by removal of mercaptans and corrosive sulphur. A further object is to provide a method of treatment which is accomplished expeditiously and with curtailment in the expense of sweetening chemicals.

I have found that an alkaline or alkali metal hydroxide solution containing cupric hydroxide acts as an efficient sweetening agent without added sulphur for obtaining refined oil products better than those obtained with a doctor treatment, more particularly, if a suspended multi-valent heavy metal sulphide is present with the cupric hydroxide to aid in settling out precipitated reaction products and to aid in the regeneration of the treating solution. A heavy metal sulphide that functions very satisfactorily in this respect is lead sulphide, but other heavy metal sulphides may be employed but with different degrees of effectiveness as, for example, cadmium sulphide or cobaltic sulphide, and the like, the preferred heavy metal sulphides being highly stable and insoluble in alkali sulphides or alkaline solutions.

In a preferred specific embodiment, the process of this invention is conducted by treating a sour or sulphur-containing hydrocarbon oil with an

5 aqueous sodium hydroxide solution containing relatively small amounts of cupric hydroxide and lead sulphide, in the presence or absence of added air or oxygen, then separating from the oil the spent treating solution and precipitated sulphur-containing reaction products. Instead of using sodium hydroxide, other closely related bases, such as potassium hydroxide or alkali metal earth hydroxides may be employed in the aqueous solution, but sodium hydroxide is preferred.

10 A suitable concentration of the sodium hydroxide in the treating solution comes in the range of about 10 to 30% by weight. Significantly, the proportion of cupric hydroxide may be rather small for satisfactory results, as, for example, about 1 to 10%. The lead sulphide or heavy metal compound, likewise, need be used in only very small amounts, generally, in a smaller weight proportion than the cupric hydroxide, e. g., about 0.1 to 5%.

15 While it has been observed that cupric hydroxide in the alkaline solution without lead sulphide or other heavy metal sulphide may be substantially as effective in purifying a sour and corrosive hydrocarbon distillate as with the lead sulphide, it was noted that a small amount of the heavy metal sulphide very advantageously favored the rate of settling and improved the regeneration of the spent treating agent. The regeneration involves oxidation as, for example, by air blowing, but the heavy metal sulphide in serving to accelerate the regeneration may be allowed to remain unchanged while the decomposition products of the spent cupric hydroxide are oxidized.

20 25 30 35 40 45 50 55 To prepare the treating agent, cupric hydroxide may be formed very simply by admixing cupric chloride with an aqueous sodium hydroxide solution or similar basic solution from which the cupric hydroxide is precipitated. The precipitated cupric hydroxide may be separated from the reaction solution and be washed free of chloride salts before being added to the alkaline solution to be used as a treating agent. However, since the amount of cupric hydroxide employed is fairly small for the present process, the amount of chloride salts formed in precipitating the cupric hydroxide is not very detrimental, so that the cupric hydroxide may be precipitated directly in the alkaline treating solution. The lead sulphide may be preformed for addition to the treating agent in any convenient manner, for example, it may be formed by passing hydrogen sulphide into an aqueous solution of a lead salt, or by reacting plumbite with sodium sulphide.

A partial regeneration of the treating agent may be effected during the sweetening operation by introducing controlled amounts of air into the treating vessel, but it is preferred to have a complete regeneration of the spent treating agent after it is separated from the sweetened oil product.

The process is adapted for either batch or continuous operation, the latter being preferred in commercial practice. The process may be carried out in conventional refining equipment like that used in a doctor treatment. A suitable form of apparatus for plant practice of the invention is illustrated diagrammatically in the accompanying drawing which shows an elevational view of the apparatus with parts in cross section.

Referring to the drawing, a sour hydrocarbon distillate is introduced into the unit through feed inlet line 1 being intimately commingled with the alkaline treating agent from line 2 in an orifice mixing device 3. The mixture from the orifice mixer is passed by line 4 into a settling tank 5 wherein a portion or all of the aqueous treating agent is separated from the oil by gravity and so that separated agent may be withdrawn from the settler by drain line 6. Partially treated oil may be withdrawn by line 7 from the first settler to a second settling tank 9, and any number of such settling tanks may be used in a series until finally the separation of aqueous treating agent from the oil is substantially completed. In the succeeding settler 9, separated spent treating agent is similarly withdrawn by drain line 10. The spent treating agent withdrawn from the settlers may be passed by line 11 to a regeneration zone wherein the spent reagent is blown with air under controlled conditions, e. g., under ordinary or elevated pressures at about 50° F. to 140° F., to regenerate the cupric hydroxide and alkaline agent. With the heavy metal sulphide present in the reagent, the oxidation in the regenera-

controlled discharge line 17, or be in part recycled to the orifice 13 by way of line 18 and the recirculation pump 19. Fresh wash water is added from line 20. The final sweetened oil product is withdrawn from the washing unit by way of line 21.

With the present method of treating, distillation of the sweetened oil is unnecessary. The treating agent may be used and regenerated repeatedly with little loss in effectiveness or quantity. The stable heavy metal sulphides employed to assist the cupric hydroxide treatment for the most part remain unaffected in their composition during the sweetening treatment and the regeneration, and accordingly, they may be regarded as being circulated without undergoing substantial change. The following specific examples on the treatment of a sour cracked gasoline will serve to illustrate how the invention is practiced and advantages derived therefrom.

Example

A sweetening agent (500 ml.) was made by adding about 28 grams of cupric hydroxide to an aqueous solution containing about 14% by weight of sodium hydroxide, and approximately 5 grams of lead sulphide were also added to the solution. About 10% by volume of this mixture was added to a sour cracked gasoline stock and agitated therewith at about 80° F. for about 3 minutes. The treated gasoline was then separated from the aqueous treating agent, and it was found to have a very satisfactory reduction in sulphur content with substantially complete elimination of mercaptans and sulphur corrosive to copper.

In further studies of this treating method, comparative tests were made on samples of a sour cracked gasoline stock with variations in the treating agents but under comparative conditions. The results are summarized in the following table:

Conditions and analyses	Procedures			
	Original cracked gasoline (as received)	Treated with Cu(OH) ₂ -PbS suspension in NaOH solution	Treated with Cu(OH) ₂ suspension in NaOH solution	Treated with PbS suspension in NaOH solution
Operation:				
Vol. per cent treating agent.....		10	10	10
Agitation, minutes.....		3	3	3
Temp., °F.....		80	80	80
Doctor test.....	Does not pass	Pass	Pass	Does not pass
Mercaptan sulphur, mg./100 ml.....	25	Nil	Nil	30
Reactive sulphur, mg./100 ml.....	0.5	Nil	Nil	3
Total sulphur, wt. per cent.....	0.186, 0.184	0.159	0.159	0.159

tion may be controlled to avoid substantial oxidation of the heavy metal sulphide, for, in general, it is preferred not to transform the heavy metal sulphide, such as the lead sulphide, into the oxide, since in the oxidized form, the lead oxide, for example, tends to alter the desired treating reaction, i. e., tends to impart the character of a doctor treatment.

The sweetened oil separated from the spent treating agent is then passed from the final settler by line 12 into an orifice mixer to be intimately contacted with wash water, then is separated from the wash water by being sent from the orifice mixer 13 through line 14 into the wash settler 15. The used wash water is separated in the settler 15 from the washed and sweetened oil and is withdrawn from the settler by line 16 to be discharged from the system through valve

All treatments were made in the presence of nitrogen gas. The data from the compared sweetening procedures indicated that the cupric hydroxide agent and cupric hydroxide-lead sulphide agent completely removed mercaptan sulphur, reactive sulphur corrosive to copper, and produced satisfactory sweet stocks according to the doctor test. However, it was noted that with the lead sulphide present, the used cupric hydroxide agent separated from the sweetened oil considerably faster and the sweetened oil was more easily water-washed than in the other treatments. Furthermore, the cupric hydroxide-lead sulphide treating agent was found to be superior to treating agents, such as doctor solution, lead sulphide-sodium hydroxide, or lead sulphide with other metal hydroxides, e. g., ferric hydroxide in an alkaline solution. This was par-

ticularly noticeable in treating cracked gasoline stocks which are difficult to sweeten owing to their high sulphur and mercaptan content.

With the high concentration of alkali and with the heavy metal sulphide present, the treated oil is kept fairly free of dissolved copper salts which tend to be detrimental to oxidation resistance of the oil, but, if desired, a small amount of an arsenite, e. g., sodium arsenite, may be used in washing the sweetened product to insure elimination of copper compounds from the oil, or any other effective measure for removal of copper may be used.

The exact treating period, proportions and temperature conditions for refining depend on the nature of the oil stock which is to be refined. It was indicated that from 5% to 30% by volume of the treating agent, a contact time ranging from 1 minute to 15 minutes, and a temperature ranging from atmospheric temperature up to 100° F. were adequate to satisfactorily sweeten sour distillates.

It is to be understood that the foregoing examples are given only for the purpose of illustration and that various changes may be made which come within the scope of the invention as defined in the appended claims.

I claim:

1. In the treatment of petroleum hydrocarbons containing mercaptans and corrosive sulphur, the step which comprises mixing the hydrocarbons

with an aqueous solution containing a caustic alkali, a minor proportion of cupric hydroxide, and a small amount of a sulphide of a multi-valent heavy metal in suspension.

5. In a continuous process of sweetening sour petroleum distillates, the improvement which comprises intimately contacting sour distillates with an aqueous sodium hydroxide solution containing a minor amount of cupric hydroxide and lead sulphide until a substantial reduction in the sulphur content of the distillate is obtained, separating the distillate of reduced sulphur content from the aqueous solution containing reacted cupric hydroxide and lead sulphide, and subjecting the thus used solution to controlled regeneration with oxygen-containing gas to regenerate the cupric hydroxide.

10. In a process of refining a sulphur-containing hydrocarbon distillate, the improvement which comprises intimately contacting the distillate with an aqueous alkaline solution containing cupric hydroxide and a minor amount of suspended lead sulphide.

15. In a process of refining a sour cracked naphtha containing corrosive sulphur, the improvement which comprises reacting sulphur compounds in the naphtha with cupric hydroxide contained in an alkaline aqueous solution and in the presence of a heavy metal sulphide suspended 20 in said solution.

HENRY C. PAULSEN.
